UNITED STATES PATENT OFFICE.

MORRIS A. HALDEMAN, OF NAZARETH, PENNSYLVANIA, ASSIGNOR TO G. A. SCHNEEBELI & CO., INC., OF NAZARETH, PENNSYLVANIA, A CORPORATION OF PENNSYLVANIA.

DESIGN FOR LACE.

47,294.

Specification for Design.

Patented May 4, 1915.

Application filed February 17, 1915. Serial No. 8,935. Term of patent 7 years.

To all whom it may concern:

Be it known that I, MORRIS A. HALDEMAN, a citizen of the United States, residing in Nazareth, Northampton county, Pennsylvania, have invented a certain new, original, and ornamental Design for a Lace, of which the following is a specification, reference being had to the accompanying drawing, forming part thereof.

The figure is a plan view of a portion of lace illustrating my new design.

I claim:

The ornamental design for a lace, substantially as shown.

MORRIS A. HALDEMAN.

Witnesses:

AUGUSTUS B. COPPES,
Wm. A. BARR.
